PLASTIC SHEET MATERIAL

John R. Ellefson, Kennett Square, Pa., assignor to E. I.
du Pont de Nemours and Company, Wilmington, Del.,
a corporation of Delaware

Filed Oct. 12, 1960, Ser. No. 62,458

Term of patent 14 years

(Cl. D87—3)

Figure 1 is a plan view of a plastic sheet material showing my new design; and

I claim:

The ornamental design for a plastic sheet material substantially as shown.
